PRINTING MACHINE

Charles Walker, Syracuse, N. Y., and Willard H. Wade, Washington, D. C., assignors to L. C. Smith & Corona Typewriters, Inc., Syracuse, N. Y., a corporation of New York

Application May 20, 1943, Serial No. 487,686

30 Claims. (Cl. 197—66)

The invention relates to improvements in printing machines of the kind wherein the printing means prints at a fixed printing line and provisions are made for imparting, between the printing means and the paper to be printed, relative advancing and retracting movements longitudinally of the printing line and also relative stepping or line spacing movements transversely of the printing line. Typewriting machines, and recording calculating machines of the traveling platen carriage type, are well known examples of such printing machines.

The improvements relate particularly to the provisions in such machines whereby the aforesaid relative movements between the printing means and paper longitudinally and transversely of the printing line of the machine are effected.

In such printing machines a line spacing means is commonly provided for imparting relative stepping movements in one direction transversely of the printing line between the printing means and paper, and the relative advancing and retracting movements longitudinally of the printing line between the printing means and paper are commonly imparted by advancing and retracting longitudinally of said line a traveling carriage or support for either the paper or the printing means. Probably the most common provision in such machines for effecting these relative movements between the printing means and paper relatively to the printing line is that wherein a traveling carriage or support is employed to advance and retract the paper longitudinally of the printing line and has mounted thereon means for line spacing the carriage-carried paper transversely of the printing line. However, other arrangements are known, for example, one well known flat platen typewriting machine wherein the printing means is carried by a traveling carriage or support which is advanced and retracted longitudinally of the printing line and which is also given line-space effecting step movements transversely of the printing line.

The invention has for its principal objects to provide, in printing machines of the kind set forth, improved power means for imparting step line spacing relative movements in a single direction transversely of the printing line between the printing means and paper; improved power means for imparting in one direction (preferably the retracting direction) relative movement longitudinally of the printing line between the printing means and paper; improved power means for concomitantly effecting the aforesaid relative longitudinal movement in one direction and trans-

verse movement in one direction with respect to the printing line between the printing means and paper; an improved key-controlled combined line spacing and carriage or supporting driving power mechanism whereby, by one depression of a single control key of said mechanism the carriage or support is driven (preferably retractively) to a selectively variable position and a single line spacing operation is completed before the driving of the carriage begins, and whereby each subsequent depression of said key while the carriage is at said position will cause said mechanism to effect another line spacing operation; and an improved key-controlled power mechanism such as last-mentioned wherein re-actuation of the control key is prevented during driving of the carriage by said power mechanism and, preferably, also wherein re-actuation of said key is prevented (after movement thereof to operation-initiating position) until the conclusion of the carriage driving action irrespective of the length of the respective time intervals required to complete the line spacing action and carriage driving action of said mechanism.

Another important object of the invention is to provide an improved power actuated carriage returning and line spacing mechanism for typewriting and like printing machines having a traveling platen carriage and a pawl and ratchet means on the carriage for rotating for line spacing purposes a roller platen carried by the carriage.

Other objects and advantages of the invention will appear from the following description of a preferred embodiment of the invention shown in the accompanying drawings.

In the drawings,
Figure 1 is a top plan view of a known form of typewriting machine equipped with improved line spacing and platen carriage returning means embodying the invention, certain parts of the machine being omitted and others partly broken away for greater clarity of illustration of the improvements.

Figure 2 is a fragmentary sectional view of the improved machine taken approximately on the line 2—2 of Figure 1, the carriage returning and line spacing means being shown in normally ineffective condition in this view and in Figure 1.

Figure 3 is a detail sectional view taken approximately on the line 3—3 of Figure 1.

Figure 4 is a detail sectional view taken on the line 4—4 of Figure 3.

Figure 5 is a detail sectional view taken on the line 5—5 of Figure 3.

Figure 6 is a view similar to Figure 4, but showing the parts positioned as at the limit of depression of the control key and instant of engagement of the driving and driven elements of the single revolution clutch hereinafter described.

Figure 7 is a sectional view on the line 7—7 of Figure 3, showing in its normal disengaged condition the carriage return driving clutch herein-after described.

Figures 8 and 9 are views similar respectively to Figures 4 and 7, but showing the parts positioned as at substantially the end of the line spacing movement of the paper, with the carriage return clutch in course of making full engagement.

Figures 10 and 11 are views similar respectively to Figures 4 and 7, but showing the carriage returning clutch in driving action with the single revolution clutch about to be disengaged and the working and return actions of the line spacing means completed.

Figure 12 is a view similar to Figure 5 showing the carriage return clutch in course of being disengaged following arrest of return travel of the carriage.

The drawings illustrate the improvements incorporated in an otherwise known typewriting machine, namely the Series 1 Super Speed L C Smith typewriting machine.

The machine has a suitable stationary main framework 10 upon which the usual platen carriage 11 is mounted in the usual manner for advance and return horizontal travel longitudinally of the printing line of the machine, i. e. transversely of the machine. The usual roller platen 12 extends horizontally transversely of the machine and is journaled in the carriage as usual to travel with the carriage.

The usual type bar segment 13 supports the usual arcuate set or system of upwardly and rearwardly swingable type bars 14, each type bar having a pivoted connection 15 with the segment and bearing a lower case type 16 and an upper case type 17, only two of the type bars being shown. The type bars are arranged as usual in the type of machine shown to print at a fixed common printing point at a horizontal printing line extending transversely of the machine, at which line the paper to be printed is backed by the platen.

The type bar segment is mounted in the main framework for shifting thereof by suitable means down and up in the main framework to condition the machine in the known manner for upper and lower case typing substantially as shown in United States patents to Gabrielson numbered 983,490, 1,018,969, 1,032,131 and 2,028,200.

The usual line spacing ratchet wheel 18, co-axial with the platen, is held to the platen adjacent one end of the carriage to rotate in unison with the platen. The usual line spacing pawl 19 is pivoted at its forward end at 20 to the upper end of the usual upstanding pawl-carrying arm 21 for up and down rocking of the pawl about pivot 20, and the arm 21 is pivoted as usual at 22 on the carriage at the lower end of said arm for fore and aft rocking of said arm. The usual torsion spring 23 is engaged with the carriage and the pawl-carrying arm to normally urge said arm forwardly as usual to a fixed normal idle position which in the improved machine is determined by means hereinafter described. The usual torsion spring 24 is engaged with the pawl

and the pawl-carrying arm to constantly tend to rock the pawl downwardly about its pivot into engagement with the toothed periphery of the ratchet wheel adjacent the top of the wheel for turning of said wheel clockwise (as viewed in Figure 2) upon each rearward swinging stroke of the pawl-carrying arm.

The usual selectively-settable regulating means is provided for varying the extent of line spacing step rotation of the ratchet wheel by the pawl. This regulating means comprises a line space regulating or pawl throw-out arm 25 which is pivoted at its lower end at 26 on the carriage for rocking adjustment fore and aft of the machine. The pawl is provided in rear of its pivot with the usual laterally extending stud 27 coactive with the usual upper arcuate cam edge of arm 25 to disengage the pawl from the ratchet wheel on each return stroke of the pawl and permit the pawl to engage and drive the ratchet wheel on each working stroke of the pawl. The usual manually settable handle arm 28 is pivoted at 29 on the carriage for fore and aft swinging adjustment of said arm, and is connected by the usual link 30 with arm 25 for adjusting the latter about its pivot to vary the point in the cycle of reciprocation of the line space pawl at which the latter will engage with and disengage from the ratchet wheel. Arm 28 is, as usual, resiliently laterally flexible to permit it to be disengaged from any one of the usual three locking notches 31 in the usual handle latching bracket 32 fixed on the carriage. The arm 28 inherently tends to snap into and remain latched in whichever one of the notches 31 it is manually registered with. Locking of arm 28 in different ones of said notches conditions the line spacing means for driving of the ratchet wheel by the pawl through different angles of rotation for single, double and triple line spacing steps, the throw of the pawl-carrying arm being constant as usual and being determined in the improved machine by means hereinafter described. The roller platen is provided with the usual finger wheel 12a for manually rotating the platen in both directions.

The usual spring-urged platen detent device is also provided comprising the usual arm 9 pivoted on the carriage at 8 for up and down rocking, the usual detent roller 7 journaled at 6 on said arm to engage between teeth of the ratchet wheel 18 at the lower part of said wheel, and the usual torsion spring 5 engaged with the carriage and arm 9 to yieldingly press roller 7 up against the toothed periphery of the ratchet wheel.

The carriage of the known machine is advanceable from right to left as usual by power from the usual spring drum (not shown) under control of the usual letter-spacing escapement mechanism (not shown) and, preferably, also under control of the usual tabulating mechanism (not shown).

The present invention is illustrated as embodied in power means for actuating the known line spacing devices above described and returning the platen carriage, return movement of the carriage from left to right being limited by the usual frame carried stop 33 and the usual adjustable margin stop 34, the latter stop being, as usual, adjustable along the usual notched margin stop bar 35 fixed on the carriage and being latchable to said bar in the usual manner at either of a plurality of letter space positions of the carriage.

The improvements as shown embodied in the known machine will now be described.

A power driven shaft 36, which extends horizontally transversely of the machine in the main framework 10 adjacent the rear end of the machine, is journaled in said framework at 37 and 38 and is constantly rotated clockwise (as viewed in Figure 2) by suitable power means while the machine is in use. Preferably, as shown, this constant power drive of shaft 36 is effected by an electric motor 39 mounted in the framework 10, which motor is constantly energized while the machine is in use and has a suitable speed-reducing driving connection 40 between its shaft 39a and the shaft 36.

A single cycle clutch mechanism of the single revolution type is provided for transmitting power from the shaft 36, said clutch mechanism including a single control key 41 located in the keyboard of the machine, and this clutch mechanism, which is of a special construction in the machine shown, will now be described.

The driving and driven clutch elements are normally disengaged. The driving clutch element is a ratchet wheel 42 fixed on shaft 36 to rotate with the latter, and the driven clutch element is a ratchet dog 43 pivoted at 44 on a dog carrier 45. A torsion spring 46 is engaged with said dog and dog carrier to constantly bias the dog to engage the ratchet wheel 42 for driving of the dog 43 and its carrier 45 by said wheel around the axis of shaft 36 in clockwise direction as viewed in Figure 2.

A mutilated pinion 47, loose on shaft 36 adjacent ratchet wheel 42, has its hub extending through the dog carrier and an arm 48 and abutting the adjacent face of ratchet wheel 42. Arm 48 is fixed to the dog carrier, as by a pin or rivet 49, and is fixed on the hub of the mutilated pinion 47 in a predetermined angularly adjusted position about the axis of said pinion. The dog 43, dog carrier 45, arm 48 and mutilated pinion 47 are thus rotatable with shaft 36 when dog 43 is engaged with ratchet wheel 42. A retaining collar 50 is fixed on the hub of pinion 47 and abuts the dog carrier 45.

The driving and driven elements of the single cycle clutch mechanism are engageable to rotate the dog carrier, and consequently also the mutilated pinion, solely and exactly 360 degrees about the axis of shaft 36 from a normal idle position in which the clutch is releasably disengaged and the dog carrier and mutilated pinion are releasably locked against rotation in both directions about said shaft axis. The control elements of this clutch mechanism will now be described.

A lever 51 is pivoted on a horizontal pivot 52 held to and extending transversely of the main frame 10, and said lever is biased by a return spring 53 to move to a normal idle position in which a stop finger 54 on said lever is urged forwardly of the machine against a fixed stop part 55 of the framework 10. Above its pivot, said lever is provided with a laterally bent lug 56 for intercepting shaft-driven rotation of the dog carrier. Also pivoted on pivot 52 is a latch arm 57 between the free upper end of which and the lug 56 there is normally closely confined the reduced end portion 58 of the dog carrier to latch the latter and the mutilated pinion 47 in normal idle position. A spring 59 is connected to lever 51 and latch arm 57 to bias the latch arm to normal latching position determined by lug 60 which is formed on lever 51 for normal engagement by the latch arm and to limit spring-urged movement of said arm. In the latched normal position of the dog carrier and mutilated pinion, the

lug 56 on lever 51 is engaged with a tail portion 61 of clutch dog 43 to hold the nose of said dog out of engagement with the driving element (ratchet wheel 42) of the clutch.

The control key 41 of the clutch mechanism is positively connected with spring-retumed means which is manually operable by depression of the key to effect conjoint rocking of lever 51 and latch arm 57 about pivot 52 in opposition to spring 53 to cause engagement of the driving and driven clutch elements. The spring-retumed means positively connected with said key will now be described. A key lever 62 has an arm pendent from a fulcrum rod 63, and a normally horizontal arm which extends forward from the pendent arm substantially midway the upper and lower ends of said pendent arm and is provided adjacent its forward end with an upstanding stem portion on the upper end of which the control key is fixed. The forwardly extending arm of the key lever is guided in one of a plurality of vertical guide slots 64 formed in a straight guide comb 65 which extends horizontally transversely of the machine and is fixed to the framework 10. Depression of the key 41 is limited by engagement of the forwardly extending arm of the lever with the closed lower end of its guide slot. The key and the means positively connected therewith are held in normal idle position by a return spring 66 which is connected with the framework and the pendent arm of the key lever to yieldingly hold the key 41 in a normal elevated position in which a pendent stop lug 67 on the forwardly extending arm of the lever is pressed forward against a straight return stop device 68 which extends horizontally transversely of the machine.

The fulcrum rod 63, preferably, is a straight rod which extends horizontally transversely of the machine to the rear of the keyboard, is fixed to framework 10, and crosses the slots of a straight horizontal row of vertical guide slots 69 formed in the machine framework, in one of which slots the upper end of the pendent arm of the key lever 62 is pivotally guided. Preferably, the key lever 62 is located adjacent the right hand side of the machine with key 41 located at the right hand end of the keyboard of the machine. Preferably, the fulcrum rod 63 serves also as the fulcrum rod for, and stop 68 as a return stop for, the type selecting key levers of key-controlled type bar actions for actuating the type bars 14 by power from shaft 36 in the manner and through the means disclosed in the co-pending application for United States patent of Charles Walker, filed November 26, 1942, Serial No. 466,989. Preferably, also, the segment 13 is shiftable for case-changing under control of two "temporary shift" keys 70 and a "shift lock" key 71 by means disclosed in our co-pending application filed February 9, 1943, Serial No. 475,264.

Journaled in the framework 10 substantially medially of the front and rear ends of the machine is a horizontal rock shaft 72 which extends transversely of the machine. Fixed on this shaft are two pendent rock arms 73 and 74, the arm 73 being substantially in fore and aft alignment with the pendent arm of key lever 62, and the arm 74 being substantially in fore and aft alignment with lever 51. A fore-and-aft extending and normally horizontal link 75 connects the lower end of the pendent arm of the key lever with the lower end of rock arm 73. To the lower end of rock arm 74 a fore and aft extending and normally horizontal tappet bar 76 is pivoted at its forward end for swinging movement in a vertical plane. Tap-

pet bar 76 is constantly guided intermediate its ends in a vertical guide slot 77 in stop part 55 of framework 10 and is normally held rocked up against the closed upper end of slot 77 by the spring 53 which is anchored to the lever 51 and to the rear end of the tappet bar. The upper edge of tappet bar 76 is cut away to provide a forwardly facing shoulder 78 and a rearwardly facing shoulder 79 which are so spaced that shoulder 78 always remains forward of slot 77 and shoulder 79 always remains rearward of said slot. Normally shoulder 79 is located immediately forward of a laterally bent lug 80 formed on lever 51 below the fulcrum of said lever.

When key 41 is depressed to its limit of downward movement, the tappet bar will be manually shoved rearward into the position shown in Figure 6 and will, through shoulder 79 and lug 80, rock lever 51 and latch arm 57 conjointly counterclockwise as viewed in Figures 2, 4 and 6, thereby unlocking the dog carrier 45 and releasing the clutch dog 43 for movement of the latter by its biasing spring 46 into engagement with the ratchet wheel 42, thus causing engagement of the clutch as shown in Figure 6.

It will be noted from Figure 6 that the shoulder 79 is still engaged in front of lug 80 at the limit of depression of the control key. Means, operable by driving of the driven clutch element, are provided for freeing the lug 80 from shoulder 79 at an intermediate point in the revolution of the driven clutch element to permit spring 53 to restore the lever 51 and latch arm 57 to normal position before a single clutch revolution is completed. A locking means carried by the tappet bar 76 is provided which acts automatically, as soon as key 41 is fully depressed to clutch-tripping position, to latch the key lever and tappet bar and the operating train therebetween against return by the spring 66. These means will now be described.

The locking means carried by the tappet bar consists of a latch 81 located at one side face of the tappet bar and pivoted thereto forward of frame part 55 at 82 for up and down swinging in slot 77 about pivot 82. A spring 83 is connected with the tappet bar and latch and normally urges the upstanding nose 85 of this latch up against the closed upper end of slot 77 to maintain the latch in a released position in which a stop lug 84 (bent laterally under the tappet bar adjacent the rear end of the latch) is spaced downward below the lower edge of the tappet bar, as shown in Figures 2, 3 and 4. The nose 85 of the latch normally extends through slot 77, but at the limit of depression of key 41 said nose is snapped up by spring 83 immediately behind stop part 55 to engage behind said part above slot 77 with lug 84 engaged under the tappet bar, as shown in Figure 6, thereby locking the key in fully depressed position and the tappet bar in fully manually rearwardly projected position as soon as the dog carrier and dog are freed for starting a cyclic rotation of the clutch.

The means operable from the driven element of the clutch for freeing lug 80 on lever 51 from the thrust action thereon of shoulder 79 on the tappet bar 76 also frees latch 81 from latching engagement with frame part 55. This means will now be described.

An arm 86, which extends rearwardly from shaft 36, has fixed thereto a hub 86a loosely pivoted on said shaft. Said arm is provided at its rear end with a laterally extending pin 87 which is normally engaged over a fore and aft extending stop lug 88 on the framework, said arm being

constantly biased by its own weight, and also further biased by means hereinafter described, to move to a normal position in which pin 87 is seated on the upper edge of said stop lug. A segment rack lever 90 is pivoted intermediate its ends on the framework at 89 to rock in the same vertical plane extending fore and aft of the machine in which the mutilated pinion 47 is located, said segment rack lever having a toothed forward arm and a rear arm which is formed with a slot 91 radial to the fulcrum of the lever. The pin 87 is slidably engaged in slot 91 and contacts both longitudinal walls of said slot. The segment rack lever is vibrative about its pivot in the normal stationary position of mutilated pinion 47 without making toothed engagement with the pinion, but the normal stationary position of the rack lever is such that, upon each revolution of the mutilated pinion, said pinion will first mesh with the teeth of said rack lever and rock the rack lever counterclockwise, as viewed in Figures 2, 4, 6, 8 and 10, through a predetermined angle of rotation determined by the number of teeth on the mutilated pinion, and will thereupon demesh from said rack lever before the pinion completes a single revolution and thus free arm 86 and the rack lever to return under the influence of the biasing force thereon to their normal idle positions during said single revolution of the pinion (as progressively illustrated in Figures 6, 8 and 10).

The hub 86a of arm 86 abuts one face of the mutilated pinion 47. Between the arm 86 and a collar 92 fixed on shaft 36 there is confined a fore and aft extending lever 93 loosely pivoted on shaft 36. Pivoted to the forward end of a forwardly extending arm of lever 93 at 94 to rock fore and aft of the machine is an upstanding lever 95 having upper and lower arms. The lower arm of this lever 95 is connected by a spring 96 with a pendent arm of lever 93, which spring is stronger than key lever return spring 66 and normally biases a rear arm of lever 93 down against a stop pin or stud 97 on arm 86. Spring 96 also constantly holds the lower arm of lever 95 pressed rearward against the closed rear end of a fore and aft extending guide slot 98 in a part 99 of framework 10. The upstanding lever 95 is formed at its lower end with a laterally bent lug 100 underneath which the shoulder 78 on tappet bar 76 is normally positioned. In the fully depressed position of key 41 and fully rearwardly projected position of the tappet bar 76, in which said key and bar are latched by latch 81, it will be noted from Figure 6 that shoulder 78 is shifted just to the rear of the path of downward movement of lug 100.

From the foregoing, and from Figures 1, 2, 3, 4, 6, 8 and 10 of the drawings, it is believed that the operation of the cyclic clutch will be obvious, but a cycle of operation thereof will be briefly described. Upon full depression of control key 41, with the parts of the cyclic clutch mechanism in their normal idle position shown in Figures 1 to 4, the tappet bar 76 is pushed rearwardly into the position shown in Figure 6. This manual rearward movement of the tappet bar causes lever 51 and latch arm 57 to conjointly rock counterclockwise (as viewed in Figures 2, 4, 6, 8 and 10) to release the clutch dog 43 and its carrier, whereupon dog 43 will be rocked by its biasing spring 46 into engagement with the driving clutch element 42, as shown in Figure 6, and the dog carrier and dog will start a driven revolution about the shaft axis in a clockwise direction

(as the parts are viewed in Figures 2, 4, 6, 8 and 10). This driven movement of the dog and dog carrier imparts a like movement to the mutilated pinion 47 which thereupon meshes with the segment rack lever, rocks said lever through a fixed arc from its normal idle position, and then demeshes from the rack lever, all before the first revolution of the driven element of the clutch is completed, and will thereafter remain demeshed from the rack lever until the next cycle of operation of the clutch.

The fixed extent of driven movement imparted from the driven element of the clutch to rack lever 90 rocks arm 86 upward a fixed extent from normal idle position, and (through pin 87) rocks lever 93 a fixed extent from normal idle position in a direction to depress lever 95 a fixed extent to rock tappet bar 76 into the position shown in Figure 10 before the mutilated pinion demeshes from segment rack lever 90. As soon as the demeshing occurs the rack lever and the arm 86 return to normal position under the constant biasing force exerted thereon.

The predetermined depression of lever 95 causes lug 100 to engage the upper edge of the tappet bar immediately in advance of shoulder 78 (as shown in Figure 8) and rock the tappet bar downward about its pivotal connection with rock arm 74 into the position shown in Figure 10, thereby disengaging shoulder 79 from lug 80 and lug or nose 85 of latch 81 from frame part 55. When this occurs, the spring 53 instantly restores lever 51 and latch arm 57 to their normal position to render them effective (as shown in Figure 10) to disengage the clutch dog and hold it disengaged and to lock the dog carrier at the end of a 360 degree driven rotation of the latter from its normal idle position, thereby also locking the mutilated pinion in its normal position after a 360 degree rotation thereof.

It will be observed that if lever 93 were formed integrally with or positively held to arm 86, the lever 95 would rise to normal position upon return of arm 86 and rack lever 90 to normal position, and that such restoration of lever 95 to normal position would first permit spring 53 to rock the tappet bar 76 upward about its pivot, thereby permitting the upper edge of the tappet bar between shoulders 78 and 79 to rise against lug 80 on lever 51, and then disengage lug 100 from shoulder 78, whereupon key lever return spring 66 would restore the key lever and tappet bar to normal position and the nose 85 of latch 81 would be carried forward into slot 77 before shoulder 79 was carried forward from beneath lug 80 of the restored lever 51.

However, in the construction shown, and for reasons hereinafter made apparent, the levers 93 and 95 are maintained in fully actuated position (shown in Figure 10) until disengagement of the carriage return driving clutch hereinafter described, whereupon they are automatically restored to idle position by spring 96 which is arranged to constantly bias them to move into normal idle position. This delayed restoration of the levers 93 and 95 is in nowise necessary to operation of the cyclic clutch, which would function if the levers 93 and 95 were permitted to return at once to their normal position under the influence of the spring 96 upon demeshing of rack lever 90 and mutilated pinion 47.

In the embodiment of the invention shown, there is provided an actuating train between the driven element of the normally disengaged cyclic clutch and the pawl carrier 21 for the line spac-

ing pawl 19 of the typewriting machine, which train is so constructed that power transmitted from shaft 36 through said clutch imparts a complete paper line spacing movement to the line space pawl during each cycle of operation of said clutch, and that a complete power-actuated vibrative or reciprocal cycle of operation of said pawl and its carrier is effected substantially instantly during each cycle of operation of said cyclic clutch.

There is also provided, in the embodiment of the invention shown, a carriage return driving train between the carriage and shaft 36, which train does not include the cyclic clutch but includes a special and normally disengaged carriage return driving clutch of the overload release type, the latter clutch being so connected with the driven element of the cyclic clutch that power transmitted from shaft 36 through the cyclic clutch during each cycle of operation of the latter causes an engaging action of the overload release clutch to occur. A cycle of operation of the cyclic clutch and a resultant cycle of operation of the line space pawl and its carrier are completed substantially instantly, and the paper line spacing stroke of the line space pawl by its carrier is completed substantially simultaneously with the engagement of the carriage return clutch. The return movement of the carriage requires a period of time which varies with the required length of return travel of the carriage and, at least in practically all cases, requires more time than is consumed in a cycle of operation of the cyclic clutch. In the embodiment of the invention shown, the carriage-returning clutch is disengaged when return travel of the carriage is arrested by the stop means 33-34 or otherwise, and remains disengaged until the cyclic clutch is again actuated whether or not the carriage is advanced following arrest thereof.

The aforesaid actuating train between the line space pawl carrier 21 and the driven element of the cyclic clutch will first be described.

A rock shaft 101, which extends horizontally transversely of the machine, is journaled at its ends in the platen carriage 11 at 102-102 at opposite ends of the carriage and rearward of the platen 12, and has fixed thereto adjacent one end thereof a pendent rock arm 103. A fore-and-aft extending link 104 is pivoted at its forward end at 105 to the line space pawl carrier 21 above the pivot 22 of the pawl carrier and is pivoted at its rear end at 106 to the lower end of rock arm 103. The rock shaft 101 has a straight bar or rail 107 fixed thereto along the forward edge of said bar or rail, said rail protruding rearward from said rock shaft throughout substantially the entire length of the carriage and forming, in effect, a rearwardly extending rock arm substantially as wide as the carriage and at least as long as the maximum length of travel of the carriage of the known machine in which the improvements are incorporated.

An upstanding thrust or tappet bar 108, comprising an upper section 108a and a lower section 108b, has journaled thereon at its upper end, on a fore and aft extending pivot 110, an anti-friction roller 109 which is always engaged under the bar 107, and said thrust bar 108 has its lower end pivotally held to arm 86 of the cyclic clutch mechanism by the pin 87 hereinbefore referred to. The lower section 108b of the thrust bar 108 is provided with superposed longitudinal

slots 111 through which extend clamping screws 112 threaded into the upper section 108a of the bar 108, whereby the overall length of the bar may be varied. The upper section 108a of the bar 108 is also provided with a longitudinal guide slot 113 through which extends a guide screw 114 threaded in a bracket 115 fixed on framework 10.

The return spring 23 for the line space dog carrier 21 constantly presses bar or rail 107 down against roller 109 on thrust bar 108. Said spring, and the weight of rail 107 and of thrust bar 108, thus augment the biasing action on arm 86 afforded by the weight of said arm 86 of the cyclic clutch mechanism by which said arm and segment rack lever 90 of said clutch mechanism are each normally maintained in an idle position determined by the frame stop 88 which is adjustably bendable up and down. These biasing forces afford power to restore the thrust bar, the line space pawl and its pawl carrier, and the operating train above described between the pawl carrier and thrust bar to a normal idle position of these connected parts which is also determined by the frame stop 88. Since the arm 86 has a fixed throw from its normal idle position imparted to said arm by power from shaft 36, it will be obvious that a fixed throw will likewise be imparted from said arm to the pawl carrier 21 and pawl 19 by power transmitted through the clutch from shaft 36.

The means whereby the platen carriage 11 is retractive drivable from shaft 36 will now be described. The normally ineffective return driving train between the carriage 11 and shaft 36 comprises a straight horizontal rack 116 which is fixed to the carriage and extends longitudinally of the carriage transversely of the machine substantially throughout the length of the carriage so as to remain in mesh with a pinion 117 at all times. Pinion 117 is fixed on the upper end of an upstanding shaft 118 journaled in framework 10. A beveled gear 119 is fixed on the lower end of shaft 118 and is in constant mesh with a beveled gear 120. Gear 120 is coaxial with shaft 36 and is drivable by the driven element of the special overload release carriage return driving clutch hereinafter described in a direction to cause retractive driving of carriage 11. Shaft 118 is preferably formed in three sections connected by universal joints 121 of well known form capable of limited telescopic adjusting motion, the upper and lower sections of the shaft being journaled in the framework 10. This arrangement permits adjustment of either the upper or lower shaft section, or both, as may be required in assembling the carriage driving train.

The special overload release clutch mechanism, whereby gear 120 is connective with and disconective from shaft 36, is constructed as follows. The driving element of said clutch consists of a ratchet wheel 122 fixed on shaft 36. A plate-like dog carrier 123 is loosely journaled on the sleeve-like hub 124 of a clutch release plate 129, which hub is loose on said shaft 36. Gear 120 is fixed on the hub of said release plate for rotation of said gear and release plate in unison. The parts 120, 123, 124 and 129 are confined between ratchet wheel 122 and a collar 125, both of which latter parts are fixed on shaft 36 with the dog carrier 123 abutting wheel 122 and the hub of gear 120 abutting collar 125, thereby preventing movement of parts 120, 123, 124 and 129 axially of shaft 36. The driven element of this clutch is a clutch dog 126 which is pivoted at 127 on the

dog carrier 123 for rocking of the dog to move its nose into and out of engagement with the toothed periphery of the ratchet wheel or driving element 122 of the clutch. A spring 128 is connected with the dog 126 and its carrier 123 to bias the dog to engage the ratchet wheel for driving of the dog and its carrier by the ratchet wheel.

Dog 126 is automatically rockable out of engagement with ratchet wheel 122 by overload release means responsive to arrest of return travel of the platen carriage 11, and said dog is, upon such release thereof, automatically latched against engagement with the ratchet wheel by automatic latching means which is releasable by power transmitted to said latching means through the cyclic clutch hereinbefore described to permit engagement of the dog with the ratchet wheel.

The clutch release plate 129 has its hub 124 loosely journaled on shaft 36 as hereinbefore described and has fixed thereto two diametrically opposed laterally extending pins or studs 130 and 131. The pin 130 extends through an arcuate slot 132 in the dog carrier and pin 131 extends through an arcuate slot 133 in said carrier, said slots being concentric with the shaft 36. To assist in maintaining the dog carrier in facewise abutted relation with plate 129, each of the pins is provided with an annular shoulder 136. The pins 130 and 131 and the slots 132 and 133 permit a limited relative rotation between the release plate and the dog carrier. A stiff pull spring 134 is connected with the dog carrier and pin 130 on the release plate 129, and a similar stiff pull spring 135 is connected with the dog carrier and pin 131 on the release plate, which springs are sufficiently stiff to drive the release plate in unison with the dog carrier during engagement of the return driving clutch but are adapted to momentarily yield slightly in starting of return of the carriage. Said springs normally yieldingly hold the dog carrier and release plate in the relatively rotated condition thereof shown in Figure 5, i. e. yieldingly hold the dog carrier retractive rotated relatively to the release plate to the limit permitted by the pin and slot connections and in a direction opposite to the direction of rotation of shaft 36 and ratchet wheel 122.

In this normal relatively rotated condition of the release plate and the dog carrier, the tail 126a of the dog 126 is retracted a substantial distance from the collar 136 on pin 131 as shown in Figure 5, and the nose of the dog is rocked outwardly entirely clear of the teeth of ratchet wheel 122. A pin 138, which projects laterally from dog 126 adjacent the nose of the dog, extends through a circular hole 139 in the dog carrier and a larger circular hole 139a in the release plate. Holes 139 and 139a are of such size and location as to afford full clearance for pin 138 when the dog 126 is in its fully engaged and fully disengaged positions with respect to the teeth of wheel 122.

It will be understood, of course, that whenever the carriage 11 is advanced, in the specific construction shown, the plate 129 and dog carrier 123 are rotated as a unit from the carriage in a direction reverse to the direction of rotation of shaft 36 and ratchet wheel 122. The limited relative rotative movement (which occurs automatically whenever return travel of the carriage is arrested) between the release plate and the dog carrier from the relatively rotated condition thereof shown in Figures 5 and 11 first advances the tail 126a of the dog 126 into contact with the

annular collar 136 of pin 131, and thereafter causes rocking of the dog fully out of engagement with the ratchet wheel during the final portion of such relative rotative movement between the release plate and dog carrier, the dog being shown partly released in Figure 12 during such relative movement. Whenever the dog 126 is thus fully disengaged from wheel 122, it is instantly automatically releasably latched in its fully disengaged position by the automatic locking means hereinbefore mentioned, which means will now be described.

A latching disk 140 having a hub 141 is normally yieldingly held abutted against the release plate 129 by spring 96 acting on said disk through a latch-shifting or latch-releasing means hereinbefore described, and is also, preferably, yieldingly held against the release plate by a spring 142, said disk being located at the opposite face of the release plate from that abutted by the dog carrier. Spring 142 is coiled about hub 124 and at its opposite ends presses against gear 120 and a flange 140a formed on hub 141 of disk 140, as shown in Figure 3. The latching disk 140 has a circular periphery, and its hub 141 is axially slideable on the hub 124 of the release plate 129 and, preferably, also is rotatively loose on said hub 124. In the normal condition of the parts, the pin 138 on dog 126 is engaged over the circular periphery of disk 140 to hold the dog latched out of engagement with the ratchet wheel 122. To free dog 126 for engagement with said wheel, the latch disk 140 and its hub are axially slideable against the biasing force of springs 96 and 142 by a latch releasing means which is operable by power transmitted from shaft 36 through the cyclic clutch, which releasing means will now be described.

A fore and aft extending latch shifting lever 143 is pivoted intermediate its ends on a vertical pivot 144 held to framework 10, said lever having a circular rear end which engages disk 140 and flange 140a. A link 145, which extends transversely of the machine, is pivotally connected at its left hand end at 146 with the forward end of lever 143 and is pivotally connected at its right hand end at 147 with the lower end of the pendent arm of a bellcrank lever 148. The bellcrank lever 148 is pivoted on the framework 10 by a fore and aft extending pivot 149 and has a second arm which extends normally horizontally toward the right hand side of the machine from the lever pivot 149. The outer end of this latter arm of the bellcrank lever 148 is forked to always engage both over and under a pivot 150 which projects forward from and is carried by the upper end of the lever 95 of the cyclic clutch mechanism hereinbefore described. Downward movement of lever 95 during a cycle of operation of the cyclic clutch mechanism will thus cause a releasing movement of latch disk 140 of the carriage return clutch mechanism with resultant engagement of the driving and driven elements of the carriage return clutch.

Operation

With the platen carriage advanced from the return limit determined by the setting of margin stop 34 of the machine, a line spacing operation of the line spacing means of the machine and a return of the platen carriage to said limit may both be effected by power upon a mere manual depression of key 41 to the limit of its depression, and these power line-spacing and carriage-returning operations will be fully completed whether or not the typist releases pressure on the

key 41. Depression of key 41, at any advanced position of the carriage, causes engagement of the driving and driven elements of the cyclic clutch and latching down of the key as shown in Figure 6 and hereinbefore described. Thereupon the mutilated pinion meshes with and drives the segment rack lever through slightly more than the first half of the ensuing revolution of the cyclic clutch as indicated in Figure 8, thus imparting a predetermined working stroke to the line space pawl carrier, whereupon, as shown in Figure 10, the arm 86, pin 81, segment rack lever 90, thrust link or tappet bar 108, the line space pawl carrier 21 and line space pawl 19 are all instantly returned to normal position by the biasing influences thereon as soon as the one-way driving connection afforded by the temporary meshing of the mutilated pinion 47 and rack lever 90 is broken.

20 The shaft-driven stroke imparted to the rack lever and arm 86 also imparts a predetermined downward stroke to lever 95 through the medium of the lever 93 and the one-way driving connection between lever 93 and arm 86 provided by pin 97. At the end of this predetermined downward stroke of lever 95, the cyclic clutch mechanism is conditioned as in Figure 10, with lever 95 now holding the key 41 still latched down as hereinbefore described. This downward stroke of lever 95 pulls the latching disk 140 of the carriage return clutch mechanism toward the right hand side of the machine far enough for pin 138 on the dog 126 of said clutch to move behind the left hand face of said disk and permit dog 126 to be rocked by its spring 128 into engagement with ratchet wheel 122, thus effecting engagement of the carriage returning clutch. Pin 138 will prevent return of latching disk 140 until the dog 126 is again disengaged from ratchet wheel 122 so that, therefore, lever 95 and lever 93 will remain in the position shown in Figure 10, and the key 41 and tappet bar 108 will also remain in the position shown in Figure 10, until dog 126 is again disengaged from wheel 122.

Upon engagement of dog 126 with ratchet wheel 122, the dog carrier 123 starts revolving with shaft 36 and, through the comparatively stiff springs 134 and 135, drives the release plate 129 and its hub 124 and the driving train 120—119—118—117—116 in a direction to return the carriage 11 toward the right hand side of the machine. The springs 134 and 135 may momentarily yield slightly upon engagement of said dog and ratchet wheel to cushion the shock of starting the carriage on its return travel.

55 Upon arrest of return travel of the carriage, rotation of parts 117, 118, 119, 120, 124 and plate 129 also stops, but the ratchet 122 will continue to drive dog 126 and the dog carrier 123 relatively to plate 129 until the springs 134 and 135 are stressed toward the extension limit permitted by slots 132 and 133 and studs 130 and 131, which relative movement of the dog carrier with respect to the arrested release plate causes the tail 126a of dog 126 to first engage the annular shoulder 136 of stud 131, as shown in Figure 12, and thereafter rock the dog fully out of engagement with ratchet wheel 122 before said relative movement of the dog carrier stops. This clutch releasing or disengaging rocking of the dog 126 carries pin 138 on the dog out far enough to permit the latching disk 140 to be snapped by springs 96 and 142 under said pin to thus relock the carriage return clutch in released condition and, also, permits the springs 96 and 142 to restore levers 95 and 93 to their normal position. Res-

toration of lever 95 to normal position releases the tappet bar 76 and key 41 for restoration to normal position by the key lever return spring 66, as hereinbefore described. Upon disengagement and re-latching of dog 126, the springs 134 and 135 will reversely rotate the dog carrier 123 relatively to plate 129 into the normal position shown in Figures 5 and 7.

With the carriage returned to the limit determined by stops 33 and 34, one or more additional line spacing operations may be effected by one or more depressions of key 41. Each such key depression will actuate the line spacing means through the cyclic clutch. On each such additional cycle of operation of the cyclic clutch the carriage return clutch will momentarily engage and will then automatically disengage and be latched in disengaged position, without any injurious strain being imposed upon any part of the mechanism.

If the typist should maintain pressure on key 41 until after lever 95 returns to normal position, no repeat cycle of operation of the cyclic clutch will occur, as will be obvious from the description of the cyclic clutch mechanism.

In the construction shown, the stop finger 67 on key lever 62 is bendably adjustable fore and aft of the machine; the downward extension of the key lever below its key carrying arm is also bendably adjustable fore and aft of the machine; and the stop finger 54 on lever 51 is also bendably adjustable fore and aft of the machine. As hereinbefore described, the length of tappet bar 103 is adjustably variable, the frame stop 88 is bendably adjustable up and down, and the upper and lower sections of the jointed and slightly extensible and contractible shaft 118 are journaled in bearings fixable to the machine frame in required position for proper location of pinion 117 and gear 119.

It will be observed that the construction described provides for a full predetermined working stroke of the line space pawl 19 during the first half (or slightly more) of each revolution of the driven element of the single-revolution clutch and for return of said pawl during the remainder of the revolution of said clutch element. This permits more rapidly successive operations of the line spacing mechanism than would be possible if the line space pawl could not start its return movement until after disengagement of the single-revolution clutch. The described arrangement also provides means readily constructible and adjustable to impart just the desired working throw to the pawl and then return it to idle position, avoids difficulties inherent in attempting to control the extent of pawl throw by duration of clutch engagement and permits use of a positive clutch for transmitting power from the power shaft to actuate the pawl.

It will be observed that the motor 39 drives the power shaft 36 through a speed reduction gearing. The usual small motor rotates at a high speed and said reduction gearing is not intended to reduce the motor speed too greatly, but merely to a convenient still high speed, for example, a shaft speed in the neighborhood of 400 R. P. M. will be found suitable for driving the line space mechanism and carriage return mechanism.

We claim:

1. In a printing machine of the class described having a main frame, a paper-carrying carriage mounted for reciprocative travel relatively to the main frame, and line spacing means on the carriage actuating upon each operation of said means to impart a selected line spacing movement to

paper carried by the carriage, the combination with said frame and carriage and line spacing means of an operation-initiating control device, a shaft journaled in the frame, power means for constantly rotating said shaft in one direction while the machine is in use, means constantly biased to couple the carriage to said shaft for driving of the carriage in one direction of its reciprocative travel and responsive to arrest of travel of the carriage in said direction to uncouple the carriage from said shaft, locking means constantly biased to automatically lock said coupling and uncoupling means against a re-coupling action thereof upon each uncoupling action thereof, and means temporarily connective with said shaft by each operation-initiating actuation of said control device to effect concomitantly by power from said shaft a single operation only of the line spacing means and a single unlocking operation only of said locking means.

2. In a printing machine of the class described having a main frame, a paper carrying carriage mounted for reciprocative travel relatively to the main frame, and means on the carriage actuating upon each operation of said means to impart a selected line spacing movement to paper carried by the carriage, the combination with said frame and carriage and line spacing means of an operation-initiating control device, a shaft journaled in the frame, power means for constantly rotating said shaft in one direction while the machine is in use, means constantly biased to couple the carriage to said shaft for driving of the carriage in one direction of its reciprocative travel and responsive to arrest of travel of the carriage in said direction to uncouple the carriage from said shaft, locking means constantly biased to automatically lock said coupling and uncoupling means against a re-coupling action thereof upon each uncoupling action thereof, means temporarily connective with said shaft by each operation-initiating actuation of said control device to effect a single operation only of the line spacing means and a single unlocking operation only of said locking means, means constantly biasing the control device to move to a normal idle position, and means controlled by the unlocking and locking operations of said locking means for respectively locking said control device in actuated position and releasing said device for restoration to its normal idle position.

3. In a printing machine of the class described, in combination, a main frame, a paper-carrying carriage mounted for reciprocative travel relatively to the main frame, means on the carriage intermittently operable to line space paper carried by the carriage, an over-load disengaging clutch having normally disconnected driving and driven elements, means connecting the carriage with the driven element of said clutch for driving of the carriage in one direction of the carriage travel while the elements of said clutch are connected, stop means for arresting travel of the carriage in said one direction, a single-revolution clutch having normally disconnected driving and driven elements, means controlled by each revolution of the driven element of the single-revolution clutch for concomitantly imparting a single operation only to said line spacing means and effecting driving engagement of the driving and driven elements of the over-load disengaging clutch, power means for constantly rotating the driving elements of said clutches while the machine is in use, and control means for causing

driving engagement of the driving and driven elements of the single-revolution clutch.

4. In a printing machine of the class described, in combination, a main frame, a platen carriage advanceable and retractable longitudinally of the printing line of the machine, a rotary platen journaled in the carriage, a line space ratchet wheel rotative with the platen, a line space pawl coactive with the ratchet wheel to rotate the latter, a shaft journaled in the main frame, power means for constantly rotating said shaft in one direction while the machine is in use, a driving train between said shaft and the carriage for retractive driving of the carriage and including a clutch, stop means for arresting retractive movement of the carriage, an oppositely shiftable actuator on the main frame biased to move in one direction to a normal idle position, means for temporarily connecting said actuator with said shaft for a movement of fixed amplitude from its idle position in opposition to its bias, a constantly maintained actuating train between said actuator and line space pawl for imparting a ratchet wheel driving stroke to said pawl upon each such movement of the actuator from idle position and for imparting an idle return stroke to said pawl upon return movement of the actuator, and means responsive to each such movement of said actuator from its idle position to effect engagement of said clutch and responsive to arrest of retractive travel of the carriage to effect disengagement of the clutch and maintain said clutch disengaged until said actuator is again moved from idle position.

5. In a typewriting, recording calculating, or like printing machine, having an advanceable and returnable paper-carrying carriage and means on the carriage for line spacing paper carried by the carriage, the combination of a power driven shaft which is constantly rotatively driven while the machine is in use, a single-revolution clutch for transmitting power from said shaft, means manually shiftable to initiate a power transmitting operation of said single-revolution clutch, a second clutch for coupling the carriage of the machine with said shaft for return driving of the carriage, means controlled from said shaft through the single-revolution clutch to render the second clutch effective and controlled from said shaft independently of the first clutch to render the second clutch ineffective until the next ensuing power-transmitting operation of the single-revolution clutch, and means operable from said shaft through said single-revolution clutch to actuate the line spacing means once during each power-transmitting operation of the single-revolution clutch.

6. In a typewriting, recording calculating, or like printing machine, having a paper-carrying carriage advanceable and retractable to traverse paper longitudinally of the printing line of the machine, line spacing means carried by the carriage and operable to move carriage-carried paper across said printing line, and stop means for arresting retraction of the carriage, the combination of a clutch mounted in the frame of the machine having normally disconnected driving and driven elements, means connecting the driven element of said clutch with the carriage for retractive driving of the carriage while the elements of said clutch are engaged, a second clutch mounted in the frame having normally disconnected driving and driven elements, power means for constantly rotating the driving elements of said clutches while the machine is in

use, means operable to connect the driving and driven elements of the second clutch for rotation of the driven element through a fixed angle only and to thereupon automatically disconnect said elements, means manually operable to initiate an operation of the last-mentioned means, means operable from the driven element of said second clutch to actuate the line spacing means once only during each rotation of said element through said fixed angle, and means rendered effective by rotation of the driven element of said second clutch to connect the driving and driven elements of the first clutch and rendered effective by retraction of the carriage to the limit determined by said stop means to disconnect said elements and maintain them disconnected until the next ensuing rotation of the driven element of the second clutch.

7. In a typewriting, recording calculating, or like printing machine, having a paper-carrying carriage advanceable and retractable to traverse paper longitudinally of the printing line of the machine, line spacing means carried by the carriage and operable to move carriage-carried paper across said printing line, and stop means for arresting retraction of the carriage, the combination of a clutch mounted in the frame of the machine having normally disconnected driving and driven elements, means connecting the driven element of said clutch with the carriage for retractive driving of the carriage while the elements of said clutch are connected, a second clutch mounted in the frame having normally disconnected driving and driven elements, power means for constantly rotating the driving elements of said clutches while the machine is in use, means operable to connect the driving and driven elements of the second clutch for rotation of the driven element through a fixed angle only and to thereupon automatically disconnect said elements, a spring-returned control device manually operable to initiate an operation of the last-mentioned means, means operable from the driven element of said second clutch to actuate the line spacing means once only during each rotation of said element through said fixed angle, means rendered effective by rotation of the driven element of said second clutch to connect the driving and driven elements of the first clutch and rendered effective by retraction of the carriage to the limit determined by said stop means to disconnect said elements and maintain them disconnected until the next ensuing rotation of the driven element of the second clutch, and means automatically enabled to prevent removal of said control device following an operation initiating manual movement of said device and automatically disabled upon disconnection of the elements of the first clutch.

8. In a typewriting, recording calculating, or like printing machine, having a paper-carrying carriage advanceable and retractable to traverse paper longitudinally of the printing line of the machine, line spacing means carried by the carriage and operable to move carriage-carried paper across said printing line, and stop means for arresting retraction of the carriage, the combination of a clutch mounted in the frame of the machine having normally disconnected driving and driven elements, means connecting the driven element of said clutch with the carriage for retractive driving of the carriage while the elements of said clutch are engaged, a second clutch mounted in the frame having normally disconnected driving and driven elements, power means

for constantly rotating the driving elements of said clutches while the machine is in use, means operable to connect the driving and driven elements of the second clutch for rotation of the driven element through a fixed angle only and to thereupon automatically disconnect said elements, a control device manually operable to initiate an operation of the last-mentioned means, means operable from the driven element of said second clutch to actuate the line spacing means once only during each rotation of said element through said fixed angle, means rendered effective by rotation of the driven element of said second clutch to connect the driving and driven elements of the first clutch and rendered effective by retraction of the carriage to the limit determined by said carriage stop means to disconnect said elements and maintain them disconnected until the next ensuing rotation of the driven element of the second clutch, and blocking means for automatically blocking a repeat of an operation-initiating operation of said manually operable control device until the driving and driven elements of the first clutch are disconnected.

9. In a printing machine of the kind set forth, in combination, means for effecting relative line spacing step movements between paper to be printed and the printing means of the machine transversely of the printing line of the machine, means traversable back and forth longitudinally of the printing line of the machine to effect relative movements between paper to be printed and the printing means of the machine lengthwise of the printing line, a rotary element which is constantly power driven while the machine is in use, a cyclic clutch mechanism for transitorily connecting the first means with said rotary element for a single actuation of said first means by power from said element, a second clutch for connecting the second means with said rotary element for driving said second means in one direction longitudinally of the printing line of the machine, governing means for said second clutch to disengage the second clutch upon movement of the second means in said one direction to a selected point and maintain it disengaged during movement of the second means in the opposite direction, and means controlled by power transmitted from said element through the cyclic clutch to effect engagement of the second clutch.

10. In a printing machine of the kind set forth having printing means for printing one character at a time on paper at a printing line of the machine, a carriage which is advanced step by step longitudinally of said line for letter spacing, and means to effect relative line spacing movements transversely of said line between the printing means and paper to be printed upon at said line, the combination with the carriage and line spacing means of a rotary element which is journaled in the machine independently of the carriage and is constantly power driven during use of the machine, a cyclic clutch connected with said element and with the line spacing means for engagement to transmit power from said rotary element to said line spacing means to actuate the latter once per cycle of operation of the clutch, a spring-returned control key connected to initiate engagement of the clutch upon depression of said key, means controlled by power transmitted from said element through said clutch to connect the carriage independently of said clutch with said rotary element for return driving of the carriage, and means controlled by arrest of return move-

ment of the carriage to disable the last-mentioned means until the clutch is again engaged.

11. In a printing machine of the kind set forth having printing means for printing one character at a time on paper at a printing line of the machine, a carriage which is advanced step by step longitudinally of said line for letter spacing, and means to effect relative line spacing movements transversely of said line between the printing means and paper to be printed upon at said line, the combination with the carriage and line spacing means of a rotary element which is journaled in the machine independently of the carriage and is constantly power driven during use of the machine, a cyclic clutch connected with said element and with the line spacing means for engagement to transmit power from said rotary element to said line spacing means to actuate the latter once per cycle of operation of the clutch, a spring-returned control key connected to initiate engagement of the clutch upon depression of said key, means controlled by power transmitted through said clutch to connect the carriage independently of said clutch with said rotary element for return driving of the carriage, means controlled by arrest of return movement of the carriage to disable the last-mentioned means until the clutch is again engaged, and means to automatically block return of said control key from depressed position until the carriage return driving means is disabled.

12. In a printing machine of the kind set forth, in combination, a paper carriage advanceable longitudinally of the printing line of the machine for letter spacing paper being printed, line spacing means on the carriage for line spacing paper being printed, a power shaft which is journaled in the machine independently of the carriage and is constantly rotated while the machine is in use, a carriage return driving clutch engageable to connect the carriage with said shaft, a cyclic clutch engageable to momentarily connect the line spacing means with said shaft for a single actuation of said means and to momentarily establish a controlling connection between said shaft and the carriage return driving clutch to cause the latter to engage for return driving of the carriage, means controlled by arrest of return movement of the carriage to disengage the carriage return driving clutch and maintain it disengaged until re-engaged through a subsequent operation of the cyclic clutch, and means manually operable to initiate an operation of the cyclic clutch.

13. In a printing machine of the kind set forth for printing on paper at a printing line of the machine, in combination, a carriage advanceable and retractable longitudinally of the printing line of the machine for varying the relation between a printing means of the machine and paper to be printed upon at said line, a power shaft which is journaled in the machine independently of the carriage and is constantly rotated while the machine is in use, a carriage driving clutch engageable to connect said shaft with the carriage for return driving of the carriage, means for disengaging said clutch upon return of the carriage to a selected point and for maintaining said clutch disengaged during advance of the carriage from said point, and means transitorily connective with said shaft for actuation by said shaft to cause engagement of said clutch.

14. In a printing machine of the class set forth for printing on paper at a printing line of the

machine, in combination, a carriage which is advanced and retracted longitudinally of the printing line of the machine to vary the relation longitudinally of said line between a printing means of the machine and paper to be printed upon at said line, a power shaft which is journaled in the machine independently of the carriage and is constantly rotated while the machine is in use, two separate trains of mechanism, two clutches each arranged for transmission of power from said shaft to a different one of said separate trains of mechanism, means for engaging a first one of said clutches, the mechanism train activative by said first clutch being connected with the second one of said clutches to cause engagement of the latter upon activation of said train from said shaft by said first clutch, the mechanism train activative by said second clutch being connected to reformatively drive said carriage, means for disengaging said first clutch after engagement of said second clutch, and means for disengaging said second clutch upon reformative driving of the carriage to a selected point and for thereafter maintaining said second clutch disengaged until said first clutch is again engaged.

15. In a printing machine of the class set forth for printing on paper at a printing line of the machine, in combination, a carriage which is advanced and retracted longitudinally of the printing line of the machine to vary the relation longitudinally of said line between a printing means of the machine and paper to be printed upon at said line, a power shaft which is journaled in the machine independently of the carriage and is constantly rotated while the machine is in use, two separate trains of mechanism, two clutches each arranged for transmission of power from said shaft to a different one of said two separate trains of mechanism, means for engaging a first one of said clutches, the mechanism train activative by said first clutch being connected with the second one of said clutches to cause engagement of the latter upon activation of said train from said shaft by said first clutch, the mechanism train activative by said second clutch being connected to reformatively drive said carriage, means for disengaging said first clutch after engagement of said second clutch, means for disengaging said second clutch upon reformative driving of the carriage to a selected point and for thereafter maintaining said second clutch disengaged until said first clutch is again engaged, and means, operative by the mechanism train which is activative by said first clutch, to effect a relative line spacing movement transversely of the printing line of the machine between said printing means of the machine and paper to be printed upon.

16. In a printing machine of the kind set forth for printing on paper at a printing line of the machine, in combination, a paper-carrying carriage mounted for advance and retraction thereof longitudinally of the printing line of the machine, a power shaft which is journaled in the machine independently of the carriage and is constantly rotated while the machine is in use, a clutch which is constantly biased to couple the carriage and shaft for reformative driving of the carriage and which also is responsive to arrest of such driving of the carriage to uncouple the carriage and shaft, means which is constantly biased to a normal position in which it prevents coupling action of said clutch following each uncoupling action of said clutch, said means being transitorily connective with said shaft for move-

ment thereby in opposition to its bias to permit coupling action of said clutch, and means for establishing a transitory connection of said biased means with said shaft.

5 17. In a printing machine of the kind set forth for printing on paper at a printing line of the machine, in combination, a paper-carrying carriage mounted for advance and retraction thereof longitudinally of the printing line of the machine, a power shaft which is journaled in the machine independently of the carriage and is constantly rotated while the machine is in use, a clutch which is constantly biased to couple the carriage and shaft for reformative driving of the carriage and which also is responsive to arrest of such driving of the carriage to uncouple the carriage and shaft, means constantly biased to move to a normal position in which it prevents coupling action of said clutch following each uncoupling action of said clutch, said means being transitorily connective with said shaft for movement thereby in opposition to its bias to permit coupling action of said clutch, and a key-controlled single-cycle clutch for transitorily connecting said biased means with said shaft.

10 18. In a printing machine of the kind set forth for printing on paper at a printing line of the machine, in combination, a paper-carrying carriage mounted for advance and retraction thereof longitudinally of the printing line of the machine, a power shaft which is journaled in the machine independently of the carriage and is constantly rotated while the machine is in use, a clutch which is constantly biased to couple the carriage and shaft for reformative driving of the carriage and which also is responsive to arrest of such driving of the carriage to uncouple the carriage and shaft, means constantly biased to move to a normal position to prevent coupling action of the clutch following each uncoupling action of said clutch and transitorily connective with said shaft for movement thereby in opposition to its bias to permit coupling action of said clutch, a single-cycle clutch for transitorily connecting said biased means with said shaft, a control key which is depressible to initiate operation of said single-cycle clutch and is biased to return to a normal position, and means for blocking return movement of said key and of said biased means to their respective positions following each depression of said key until the ensuing uncoupling action of the first-mentioned clutch.

15 19. In a printing machine of the class set forth for printing on paper at a printing line of the machine, the combination of means biased to move to a normal idle position from which the same is movable to cause a line spacing shift transversely of the printing line between a printing means of the machine and paper to be printed upon by the printing means, a power shaft which is journaled in the machine and is constantly rotated while the machine is in use, a single-revolution clutch having a driving clutch element constantly connected with said shaft and a driven clutch element normally disengaged from said driving clutch element, control means for causing engagement of the driving and driven clutch elements of said single-revolution clutch, and automatically engageable and disengageable means arranged to move said biased means in opposition to its bias a fixed extent from normal position by power transmitted through said clutch following each engagement of said clutch elements and to thereupon immediately free said

biased means for unobstructed biased return movement prior to disengagement of said clutch elements.

20. In a printing machine of the class set forth having means for printing on paper at a fixed printing line of the machine, the combination with said printing means of a ratchet wheel rotative to change the relation with respect to the printing line between said printing means and paper to be printed upon, a pawl which is normally disengaged from said wheel and is biased to move to a fixed normal position, a rotary element which is journaled in the machine and is constantly rotated while the machine is in use, means connective at will with said rotary element for a single rotative movement only thereof of fixed extent in one direction, and means automatically movable a fixed extent only by each such rotative movement of said connective means to first actuate said pawl a fixed extent in ratchet wheel driving direction and to thereupon immediately automatically free said pawl for unobstructed biased return movement of said pawl prior to disconnection of said connective means from said rotary element.

21. In a printing machine of the class set forth having printing means for printing upon paper at a fixed printing line of the machine, a platen carriage movable longitudinally of said line, a roller platen extending longitudinally of said line and journaled in the carriage for rotation about an axis parallel to said line, and a ratchet wheel rotative with the platen, the combination with said carriage and platen and wheel of a line spacing pawl and actuating means therefor both of which are mounted on the carriage for actuation of said pawl to rotate said ratchet wheel and are biased to move to a normal idle position in which the pawl is disengaged from said ratchet wheel, a rotary element which is journaled in the machine independently of said carriage and is constantly rapidly rotated while the machine is in use, rotative means transitorily connective with said rotary element for a predetermined angular rotation only of said means by said element, reciprocal driving means for said pawl-actuating means mounted independently of said carriage and constantly connected with the pawl-actuating means and biased to return to a normal idle position, and means for automatically making, during each connection of said transitorily connective means with said rotary element, a ratchet-wheel-rotating pawl-driving connection between said transitorily connective rotative means and said reciprocal driving means throughout a predetermined fixed fraction of the rotative movement of said transitorily connective rotative means by said rotary element and thereupon immediately breaking said pawl-driving connection and maintaining it broken until said rotative means is first disconnected from and again connected with said rotary element.

22. In a printing machine of the class set forth having printing means actuating to print on paper at a fixed printing line of the machine, the combination with said printing means of a ratchet wheel which is rotative to cause a line spacing shift transversely of said printing line between said printing means and paper to be printed upon, a pawl which is normally disengaged from said ratchet wheel, a shaft which is journaled in the machine and is constantly rotated while the machine is in use, rotative means transitorily connective with said shaft for rotative driving of said means through a fixed angle of rotation by the

shaft, and reciprocative actuating means for said pawl biased to return to a normal idle position and arranged to be first moved by said rotative means for a fixed extent in opposition to its bias to actuate said pawl to rotate said ratchet wheel and thereupon immediately freed from said rotative means for unobstructed biased return movement of said reciprocative means during each period of driving connection of said rotative means with said shaft.

23. In a printing machine of the class set forth having printing means actuating to print on paper at a fixed printing line of the machine, the combination of a toothed wheel rotative to vary the relation relatively to said line between said printing means and the paper to be printed upon, a reciprocative member engageable with a tooth of said wheel to rotate the wheel upon movement of said member in one direction only, a reciprocative rack which is connected with said member to move the latter in wheel rotating direction, said member and rack being both biased to return to a normal idle position, a mutilated pinion rotative to drive said rack a fixed distance from its idle position in a direction to import wheel rotative movement to said member, a power shaft which is constantly rotated while the machine is in use, and a single-revolution clutch mechanism for coupling said mutilated pinion to said shaft for rotation of the pinion 360 degrees only from a normal idle position in which the pinion is demeshed from the rack, said rack and pinion being arranged to mesh once during each rotation of the pinion and to demesh prior to completion of each rotation of the pinion, and said rack and member being movable to normal idle position immediately upon demeshing of the rack and pinion.

24. In a printing machine of the class set forth having printing means actuating to print on paper at a fixed printing line of the machine, the combination of a power shaft which is constantly rotated while the machine is in use, a reciprocal rack biased to return to a normal idle position, line spacing means, including an actuating train reciprocal with the rack, for varying the relation transversely of said printing line between the printing means and paper, a mutilated pinion rotative to drive said rack in opposition to its bias a fixed extent to actuate said line spacing means, a single-revolution clutch mechanism for coupling said pinion to said shaft for rotation of the pinion a single revolution only from a normal idle position in which the pinion and rack are demeshed, said rack and pinion being arranged to first mesh and thereafter demesh during each rotation of the pinion, and said rack being arranged for return movement toward its idle position immediately upon demeshing of the rack and pinion, means variably drivable to change the relation longitudinally of said printing line between the printing means and paper to be printed, a clutch controlled by driving movement of said rack by said pinion to couple said variably drivable means with said shaft for driving of said means by said shaft, and means for disengaging the last-mentioned clutch and maintaining it disengaged until the next ensuing operation of the single-revolution clutch.

25. A printing machine of the class set forth having, in combination, a main frame, a platen carriage which is advanceable and retractable transversely of said frame longitudinally of the printing line of the machine, a roller platen journaled in said carriage and extending trans-

versely of the machine, a line spacing ratchet wheel held to the platen for rotation therewith, a line spacing pawl, means mounted in part on the frame and in part on the carriage constantly connected with said pawl for actuation to drive said pawl to rotate said wheel and biased for return thereof and of said pawl to a normal idle position, means mounted in part on the frame and in part on the carriage and constantly connected with the carriage for actuation of said means to retractively drive the carriage, means to arrest retractive driving of the carriage, a shaft journaled in the frame and which is constantly power rotated while the machine is in use, a clutch biased to engage to connect the second mentioned means to said shaft for actuation by the shaft, means controlled by power transmitted through said clutch to disengage said clutch upon arrest of retractive driving of the carriage, a latch biased to normally lock said clutch against engagement upon disengagement of the clutch and movable to permit engagement of said clutch, a key-controlled cyclic clutch biased to engage to transmit power from said shaft, means movable by said cyclic clutch throughout engagement of the clutch to first actuate and then release the first-mentioned pawl-actuating means, and means forming a one-way motion transmitting connection between said pawl-actuating means and said latch for moving the latch to permit engagement of the first-mentioned clutch substantially at the end of the ratchet wheel driving movement of the line space pawl.

26. A printing machine as claimed in claim 25, having means for inhibiting both restoration of said latch to latching position and re-engagement of said cyclic clutch while the other clutch is engaged.

27. In a printing machine of the class set forth having printing means for printing on paper at a fixed printing line of the machine and a carriage which is advanceable and retractile longitudinally of said line for varying the relation longitudinally of said line between said printing means and paper to be printed upon, the combination with said carriage of a shaft journaled in the machine independently of the carriage, power means for constantly rotating said shaft while the machine is in use, a ratchet wheel fixed to said shaft, a dog carrier loose on said shaft, a dog pivoted on said carrier for movement into and out of engagement with said ratchet wheel and for rotation of the dog and carrier by and about said shaft while the dog is engaged with said ratchet wheel, driving means constantly geared to the carriage and including a rotative element loose on said shaft and connected with said dog carrier for limited relative rotation between said element and dog carrier about the axis of said shaft, a spring connecting the dog and its carrier to bias the dog to engage the ratchet wheel, spring means yieldingly connecting the dog carrier and element for driving of the element by said carrier about said shaft in a direction to retractively drive the carriage during engagement of the dog with the ratchet wheel and which is yieldingly extensible upon arrest of retractive driving of the carriage to permit limited continued rotation of the dog carrier relatively to said element, means on said element engageable by the dog during such limited continued rotation of the dog carrier to disengage the dog from the ratchet wheel, a latching disk slidable axially of said shaft and biased to move to a normal

latching position, a lateral projection on the dog which is normally engaged over the periphery of the disk for latching of said dog by the disk out of engagement with the ratchet wheel and which is abutted by a face of said disk to hold the disk in unlatching position when the dog is engaged with said wheel, and means transitorily connective with said shaft for power movement thereof by the shaft to shift said disk axially of the shaft from its normal position to permit engagement of the dog with the ratchet wheel.

28. In a printing machine of the class set forth, in combination, a ratchet wheel rotative for effecting a line spacing movement between printing means of the machine and paper to be printed upon, a rotatively mounted shaft which is constantly and rapidly rotatively driven while the machine is in use, a second ratchet wheel fixed on said shaft, a mutilated pinion and a dog carrier loose on said shaft and connected for rotation as a unit about the axis of said shaft, a dog mounted on said carrier for movement into and out of engagement with said second ratchet wheel and biased to engage said wheel for driving of the dog carrier and pinion with said shaft, means biased to a normal idle position for effecting disengagement of said dog from said second ratchet wheel and for thereupon holding the dog carrier and pinion against rotation at a fixed rotated position of said carrier and pinion about said shaft with said dog disengaged, a reciprocative rack and a pawl connected and biased for movement thereof to a normal idle position in which said pawl is disengaged from the first-mentioned ratchet wheel and said rack is demeshed from said pinion, said rack being first drivable from its normal position a pre-determined extent by said pinion and then restorable to normal idle position during each revolution of said pinion from the held position of the pinion, key operated means for moving said biased means to release the dog and dog carrier, and means movable by said rack during driving of the latter by said pinion to disconnect said key operated means from said biased means prior to completion of a single revolution of the pinion upon each actuation of said key operated means.

29. In a printing machine of the class set forth having printing means actuating to print on paper at a printing line of the machine, the combination of a toothed wheel rotative to vary the relation with respect to said line between the printing means of the machine and paper to be printed upon by said means, a reciprocative member coactive with the teeth of said wheel to rotate said wheel one step at a time, a reciprocative rack connected with said member, said member and rack being biased to move to a normal idle position in which said member is disengaged from said wheel, a shaft which is journaled in the machine and constantly and rapidly power rotated while the machine is in use, a ratchet wheel fixed on said shaft, a dog carrier and a mutilated pinion loose on said shaft and connected for rotation as a unit, a dog mounted on the dog carrier for movement into and out of engagement with the ratchet wheel and also biased to engage said ratchet wheel for rotation of the dog and its carrier and said pinion as a unit with said shaft while the dog is engaged with the ratchet wheel, means biased to move to a normal idle position for effecting disengagement of said dog from said ratchet wheel and holding said dog carrier and pinion against rotation at a fixed rotated position of the dog carrier and

pinion about said shaft with the dog disengaged from the ratchet wheel, said pinion being normally disengaged from said rack and arranged to, during each revolution of the pinion, first mesh with and drive said rack a fixed extent and then demesh from and remain demeshed from said rack until the next revolution of said pinion, key operated means for moving said biased disengaging and holding means to release the dog carrier and dog, and means movable by the rack during each driving of the latter by the pinion to disconnect said biased disengaging and holding means from the key operated means prior to completion of a single revolution of the pinion.

30. In a printing machine of the class described, the combination of a toothed wheel rotative to change the relation with respect to the printing line of the machine between printing means of the machine and paper to be printed upon by said means at said line, a rotatively journalled power shaft which is constantly and

rapidly power driven while the machine is in use, a key-tripable and normally disengaged single-revolution positive clutch having driving and driven elements biased to engage and positively engageable for transmitting power from said shaft, oppositely movable wheel actuating means biased to move to a normal idle position and movable in opposition to its bias for coaction with the teeth of said wheel to rotate the latter, and means forming an automatic make-and-break motion transmitting connection between said wheel actuating means and the driven element of said clutch arranged to, during each revolution of the driven element of said clutch, first move said actuating means in opposition to its bias a fixed extent and thereupon free said actuating means for unobstructed return to its normal idle position at a rate independent of the rate of revolution of the driven element of the clutch.

CHARLES WALKER,
WILLARD H. WADE.
